UNITED STATES PATENT OFFICE.

JAMES C. CAIRNCROSS, OF OMEMEE, NORTH DAKOTA.

AUTOMATIC STEAM AND LEVER PLOW-LIFT.

987,696.

Specification of Letters Patent. Patented Mar. 28, 1911.

Application filed April 9, 1910. Serial No. 554,372.

To all whom it may concern:

Be it known that I, JAMES C. CAIRNCROSS, a citizen of the United States of America, residing at Omemee, in the county of Bottineau and State of North Dakota, have invented certain new and useful Improvements in Automatic Steam and Lever Plow-Lifts, of which the following is a specification, reference being had therein to the accompanying drawing.

This invention relates to the subject of plows, and the principal object of the same is to provide novel coupling means for pivotally connecting a plow to a source of draft power, said pivotal coupling frame permitting independent movement of the plow relative to the draft, so that the plow may be raised either automatically or manually in the event of an obstruction being contacted with.

The improved coupling means may be used in connection with any type of draft power and in its preferred embodiment the same is especially adapted for use in connection with a traction engine or other motor, means being provided whereby the coupling means will automatically release the plow should an obstruction be reached from which the plows cannot become disengaged, thereby preventing damage being done to the plows.

In carrying out the objects of the invention generally stated above, it will be understood, of course, that the essential features of the invention are necessarily susceptible of changes in details and structural arrangements, practical embodiments of which are shown in the accompanying drawings, wherein—

Figure 1 is a top plan view of a plow equipped with the improved lift. Fig. 2 is a side view thereof. Fig. 3 is a similar view, showing the plow shares elevated to pass an obstruction. Fig. 4 is a view in side elevation of the coupling frame and the forward gage wheel frame. Fig. 5 is a fragmentary detail view. Fig. 6 is a perspective view of a plow showing a manually operable lift applied thereto. Fig. 7 is a side elevation thereof, showing the plow shares elevated.

Referring to said drawings by numerals, and more particularly to Figs. 1, 2, 3, 4 and 5 thereof wherein the plow is of the motor-operated type, it will be seen that the plow frame is composed of parallel beams 1—2, 55 which are retained in spaced relation by the

transverse bars 3—4. The downturned rear ends of said beams carry plow shares 5. At their forward ends, said beams are connected by a pivot shaft 6.

Adjacent their rear ends, beams 1—2 have a gage wheel frame 7 pivotally connected thereto in which the wheel 8 is mounted. A forward gage wheel frame 9, preferably formed U-shaped, has its side members provided with an inclined bearing slot 10 for the pivot shaft 6. A dog 11 is pivotally mounted on the side members of frame 9 above the slots 10, said dogs provided with a bearing recess 12 which engages shaft 6 to normally retain the same in slots 10 of frame 9. A wheel 13 is mounted in frame 9.

A coupling frame composed of parallel side members 14 which are retained in spaced relation by the reinforcing truss 15 has the lower ends of its side members pivotally and adjustably connected to the lower portion of frame 9 by the pivot bolts 16 and nuts 17. The free ends of members 14 are connected by a pivot bolt 18 upon which a link 19 is mounted that is adapted for connection with a motor (not shown). Coiled springs 20 connect dogs 11 to the projected ends of bolt 18, said springs being fastened to bolt 18 by the nuts 21.

Rear gage wheel frame 7 has its free end adjustably connected to the rear of the plow frame by the hand screw 22. The rear end portion of the plow frame has a cable 23 connected thereto, said cable extending from a hoisting cylinder (not shown) and passing over a crane 24. This arrangement provides means whereby the plow may be lifted from the ground by the motor when not in use, or to facilitate turning.

In operation, assuming the plow to be in the position shown in Fig. 2, it will be seen that should the plow shares strike an obstruction, the forward gage wheel frame 9 will be pulled toward a vertical position which elevates the forward end of the plow frame so that the plow shares are tilted to the position shown in Fig. 3 to permit the plow shares to ride over the obstruction. Should the obstruction be of such nature that the plow shares are not released by elevating the forward end of the plow frame, it will be seen that the continued forward movement of the frame 9 will cause slots 10 and dogs 11 to assume such position that shaft 6 will be released,

thereby freeing the plow frame from the motor and obviously prevent damage being done to the plow or its frame.

In Figs. 6 and 7, the plow is especially adapted for use in connection with light draft power, and in plows of this type it is clear that there is no necessity for the employment of means for automatically releasing the plow frame from its connection with the draft. In this form of the invention, the forward gage wheel frame and the rear gage wheel frame are connected by a link 25 so that they will swing together. The forward gage wheel frame is provided with a hand lever 26 by means of which said frames may be simultaneously operated to raise or lower the plow.

What I claim as my invention is:—

1. A plow comprising a supporting frame, a pivot bolt carried by the forward end thereof, a gage wheel frame detachably connected to said pivot bolt, a coupling frame pivotally connected to said gage wheel frame, dogs carried by the gage wheel frame for normally retaining the same engaged with said pivot bolt, and means carried by said coupling frame for releasing said dogs.
2. A plow comprising a supporting frame, a gage wheel frame detachably connected thereto, a coupling frame pivotally connected to said gage wheel frame, means for normally retaining said gage wheel frame engaged with the supporting frame, and means actuated by the coupling frame for releasing the gage wheel frame.

3. A plow comprising a supporting frame, a pivot bolt carried by the forward end thereof, a gage wheel frame loosely mounted on said frame, a draft coupling pivotally connected to said gage wheel frame, dogs 40 carried by the gage wheel frame and normally engaging said pivot bolt, and springs connecting said dogs to said draft coupling.

4. A plow comprising a supporting frame formed of spaced parallel members, a pivot 45 bolt connecting the forward ends of said members, a gage wheel frame detachably engaging said pivot bolt, means for normally retaining said gage wheel frame in a pivotal engagement with said bolt, a coupling frame 50 pivotally connected to said gage wheel frame, and means carried by said coupling frame for releasing the gage wheel frame from said pivot bolt.

5. A plow comprising a supporting frame, 55 a pivot bolt at the forward end thereof, a gage wheel frame provided with slots for detachable pivotal engagement with said bolt, dogs carried by said gage wheel frame for normally holding said gage wheel frame 60 engaged with said bolt, a coupling frame pivotally connected to said gage wheel frame, and springs carried by said coupling frame and engaging said dogs.

In testimony whereof I hereunto affix my 65 signature in presence of two witnesses.

JAMES C. CAIRNCROSS.
